CLAIM

1 Claim, 1 Drawing Sheet

The ornamental design for an shoe outsole, as shown and described.

DESCRIPTION

FIG. 1 is a perspective view of a shoe outsole showing my new design; and,

FIG. 2 is a bottom view of a shoe outsole shown in FIG. 1. The uneven broken line immediately adjacent to the shaded area represents the bounds of the claimed design. All other uneven broken lines represent the remaining portion of the shoe. The uneven broken line representations in FIGS. 1-2 are for illustrative purposes only and form no part of the claimed design.

FIG. 1

FIG. 2
